(57) **CLAIM**

The ornamental design for a telescopic roll up dish drying rack, as shown and described.

DESCRIPTION

FIG. 1 is a front elevational view of a telescopic roll up dish drying rack showing my new design;

FIG. 2 is a rear elevational view thereof; and

FIG. 3 is a left elevational view thereof;

FIG. 4 is a right side view thereof;

FIG. 5 is a top side view thereof;

FIG. 6 is a bottom plan view thereof;

FIG. 7 is a perspective view of a telescopic roll up dish drying rack showing my new design; and,

FIG. 8 is a perspective view showing the telescopic roll up dish drying rack is in a rolled-up state.

1 Claim, 8 Drawing Sheets(56)
